ANTHONY T. STOCK, OF DAYTON, OHIO, ASSIGNOR TO FRIGIDAIRE CORPORATION, OF DAYTON, OHIO, A CORPORATION OF DELAWARE

REFRIGERATING APPARATUS

Application filed January 31, 1928. Serial No. 250,835.

This invention relates to improvements in refrigerating apparatus and more particularly to the condenser used in connection therewith.

- 5   It is one of the objects of the invention to provide an air-cooled condenser which is particularly efficient and which requires less space and tubing than condensers used heretofore.
- 10   It is a further object of the invention to provide an improved construction for supporting and arranging the condensing system of the apparatus so that the same may be efficiently cooled.
- 15   A still further object is to improve the layout of the compressor unit generally and to provide a compact symmetrical arrangement of the condenser therein.

In carrying out the above objects, the invention contemplates providing a condenser which is arranged to conform in shape to the shape of the blast of air produced by a fan. This is effected by arranging the ducts of the condenser linearly in an annular space 25 through which the air blast is forced.

This invention is particularly applicable to refrigerating apparatus of the type in which the refrigerating effect is produced by evaporation of a liquefied gas or the expansion of a 30 compressed gas. The apparatus is especially designed to use a refrigerant of low boiling point such as sulphur dioxide.

In devices of this kind the liquefied gas such as sulphur dioxide is allowed to boil off or 35 expand in a refrigerating element which is arranged to transfer the heat from the surrounding air to the refrigerant. The gas resulting from the vaporization of the refrigerant is deprived of its heat by being forced by 40 the compressor into a condenser where it is again converted into a liquid. In the case of air-cooled condensers, it is customary to arrange them in the form of coils, spirals and the like which are mounted at a convenient 45 place in the compressor unit assembly and preferably in such a manner as to expose the condenser to the cooling action of a blast of air created by a fan or blower. The cooling action so produced is not always sufficient 50 and various expedients have been suggested

such as deflectors and the like for forcing the cooling air into better contact with the condenser.

By means of the present invention, efficient cooling of the condenser is effected by arranging the condenser around the body of the motor used for driving the compressor and providing means for forcing sufficient air through the coils of the condenser. 55

Further objects and advantages of the present invention will be apparent from the following description, reference being had to the accompanying drawing, wherein a preferred form of the present invention is clearly shown. 60

In the drawings:

Fig. 1 shows the improved condenser arrangement of the invention applied to a refrigerating system, showing a side elevation of the condenser and compressor with the refrigerating circuit indicated diagrammatically, and 70

Fig. 2 is a side view of the condenser taken on the line 2-2 of Fig. 1. 75

Referring in detail to the drawings, the refrigerating system comprises a compressor having a cylinder 10 in which reciprocates a piston connected with a crank in the crank case 11 and which piston is operated through such crank by means of the belt driving wheel 12. The compressor is operated by means of an electric motor 13 provided with a pulley 14 and belt 15 which cooperates with belt driving wheel 12. Both motor and compressor may be mounted on a base 16 as shown in Fig. 1 which may in turn be provided with legs 17. 80

The improved condenser of the invention consists of a coil of pipe 18. This coil consists of a plurality of linearly arranged loops having a length preferably equal to that of the body of the motor and extending in the same direction as the shaft of the motor as shown in Fig. 2. One of the individual linear ducts of each loop co-operate with like portions of the other loops to define an arc, while the other individual linear ducts of the loops are similarly disposed and are substantially coaxial with the first and these ducts are connected at their ends 39 as shown in Fig. 1. 90

It is therefore apparent that the space in which the condenser is located is an arcuate space like a substantially annular cylinder with a portion cut away at the bottom and that the confines of the space are bounded by the internal and external linear ducts which constitute the elements of a pair of substantially parallel cylindrical and coaxial surfaces.

10 The condenser, consisting of a coil formed of these linear ducts connected at their bent ends 39 into horizontal loops as above described, is draped around the body of the motor so as to produce a sort of tunnel-shaped or arcuate archway around the motor. It is preferably spaced away slightly from the body of the motor and a shield 22 consisting of a similarly shaped piece of metal is preferably interposed between the body of the 20 motor and the innermost arcuate layer of linear pipes and is likewise spaced from both the motor body and the internal layer of ducts. The function of the shield, above described, is to aid in promoting an efficient 25 draft of air through the coils of the condenser and to prevent any heat engendered by the motor itself from being radiated directly against the condenser coils. The shield may be fastened to the motor as by 30 the mounting bolts 23. The motor itself for convenience in assembly and connection of the condenser may be mounted upon a bracket 24 held in place by bolts 25 which may also hold the internal supporting straps 35 21 in place.

While the condenser may comprise one continuous coil, it may also be divided into a plurality of units suitably connected together. In the preferred embodiment of the 40 invention two arcuate unit coils are used which extend vertically upward for a considerable distance from a point near the legs of the motor whereupon they follow the curvature of the body of the motor and terminate at 26, 27 in the coupling element 28 which connects them to the common pipe 29. A similar scheme of connections is used at the bottom, a suitable coupling 40 being used for the purpose.

50 The coil of pipe constituting the condenser is held in place by means of straps 19 retained in place by suitable screws 20 cooperating with similar straps 21 disposed inside of the condenser coil and contacting with the innermost layer of ducts.

A fan 38 for cooling the condenser may be disposed at any suitable point in operative relation to the condenser but in the preferred embodiment of the invention it is mounted on 60 the motor shaft so that its rotation will force a strong current of air between the coils and the condenser and through the tunnel-like archway formed by the shell 22 and the coil of pipe. This blast of air will quickly and 65 efficiently cool the condenser.

It is a characteristic of a fan of this type to produce an annularly shaped blast of air which has its greatest effect confined in an annulus substantially remote from the shaft and adjacent the periphery of the blades. 70 By shaping the condenser to correspond to this annulus it is evident that the entire body of the condenser will be in the direct path of air of the highest velocity and that maximum cooling effect will be obtained. Since 75 the ducts are arranged parallel to the direction of flow of the air, they will be swept by this high velocity air and hence substantially the entire surface of the coil will be cooled.

In the operation of the apparatus, the refrigerating medium, which may for example be sulphur dioxide, is allowed to evaporate in the refrigerating element composed of coils 31 to which it is supplied by means of a header 32. The refrigerant is supplied through a pipe 33 and its supply is controlled by means of a float valve or the like within the header 32. It will be appreciated that an expansion valve may also be used, the principle in either case being the same, the refrigerating effect being produced by the exchange of heat between the air or the material to be cooled and the refrigerant supplied to the refrigerating element. After the refrigerant absorbs heat 90 it boils off and is withdrawn through pipe 34 and returned to the compressor at the point 35. The gas is then compressed and forced into the condenser above described through pipe 29 from which it collects as liquid sulphur dioxide in a receiver 36 through pipe 37, the receiver being shown as a small tank conveniently positioned for example between the legs of the base upon which the compressor unit is mounted. From the receiver 36 100 the liquid sulphur dioxide passes by way of pipe 33 back to the header 32 and thence to the coil 31 whereafter the cycle of operation is repeated.

Since the body of the condenser is located 110 directly and entirely in the annular space bounded by the internal and external linear ducts and since the fan produces an annular blast of air of approximately the same shape as the condenser and forces the same through the condenser, it is obvious that efficient cooling of the coils will be effected. Furthermore, since all of the effective heat radiating area of the condenser lies in the path of the air blast, a lesser amount of tubing may be 115 used.

By the above arrangement a very compact condenser is provided which is extremely effective in operation and which economizes in the amount of tubing required, while at the same time providing a comparatively rigid structure. The compressor unit is also substantially simplified since no coil systems are loosely placed therein to be subject to damage or in the way when repairs are needed. 130

While the form of embodiment of the invention as herein disclosed constitutes a preferred form, it is to be understood that other forms might be adopted, all coming within the scope of the claims which follow.

5 What is claimed is as follows:

1. Refrigerating apparatus comprising a motor, a plurality of ducts constituting a condenser and draped in arcuate form around the outside of the body of said motor, a shield between the body of said motor and said condenser and a fan adapted to force air about said ducts.
- 10 2. Refrigerating apparatus comprising a motor, a condenser comprising a plurality of ducts disposed on a plurality of sides of said motor, and shielding means interposed between said motor and said ducts.
- 15 3. Refrigerating apparatus comprising a motor, a condenser including ducts disposed around the outside of the body of said motor, a shield between the body of said motor and said condenser, and a fan adapted to force air about said ducts.
- 20 4. Refrigerating apparatus comprising a motor, a condenser including a coil disposed on one side of the body of said motor, a coil disposed on the opposite side of the body of said motor, the ends of said coils merging toward each other above the motor and connected in parallel circuit relation, and a fan to force air about said coils.
- 25 5. Refrigerating apparatus comprising a motor, a condenser including loops on each side of the body of said motor, said loops each including double row portions, and a fan adapted to force air about said double row portions.
- 30 6. Refrigerating apparatus comprising a motor, a condenser including pipe coils having loop portions extending longitudinally of the motor and disposed around the outside of the body of said motor, and a fan adapted to force air about said coils.
- 35 7. Refrigerating apparatus comprising a motor, a condenser including pipe coils having loop portions extending longitudinally of the motor and disposed around the outside of the body of said motor, a shield between the body of said motor and said condenser, and a fan adapted to force air about said coils.
- 40 8. Refrigerating apparatus comprising a motor, a condenser including pipe coils having loop portions extending longitudinally of the motor and disposed in arcuate form around the outside of the body of said motor, and a fan adapted to force air about said coils.

In testimony whereof I hereto affix my signature.

ANTHONY T. STOCK.
